UNITED STATES PATENT OFFICE.

HOWARD A. SMITH, OF MONTGOMERY, IOWA.

HAYRACK-FASTENER.

1,400,834.

Specification of Letters Patent. Patented Dec. 20, 1921.

Application filed September 8, 1919. Serial No. 322,272.

To all whom it may concern:

Be it known that I, HOWARD A. SMITH, citizen of the United States, residing at Montgomery, in the county of Dickinson and 5 State of Iowa, have invented certain new and useful Improvements in Hayrack-Fasteners, of which the following is a specification.

This invention relates to improvements 10 in hay rack fasteners especially adapted for securing hay racks to the bolsters of farm wagons.

An important object of this invention is to provide a hay rack fastener adapted to 15 be secured to the bed of a hay rack for preventing the bolster from wearing into the bed of the hay rack as the result of relative movement of the bed of the hay rack and the bolster.

20 A further object of the invention is to provide a hay rack fastener which when applied will effectively serve to secure the hay rack in an adjusted position with relation to the bolster and will prevent the hay rack 25 from partaking of longitudinal movement with relation to the bolster.

A further object of this invention is to 30 provide a hay rack fastener which is simple to apply, efficient in use and of highly simplified construction.

Other objects and advantages of the invention will be apparent during the course 35 of the following description.

In the accompanying drawing forming 40 a part of this application and in which like numerals are employed to designate like parts throughout the same:

Figure 1 is a side elevation of the hay 45 rack fastener in use;

Fig. 2 is a perspective view of the several 50 elements of the invention detached.

In the drawing wherein for the purpose 55 of illustration is shown a preferred embodiment of the invention, the numeral 5 generally designates a farm wagon including a bed 6 and an axle 7 supported by wheels 8.

A bolster 9 extends transversely of the 60 wagon bed and is provided with bolster stakes 10 extending vertically from its ends.

55 A hay rack bed generally designated by the numeral 11 is mounted upon the bolster 9 and includes longitudinally extending side beams 12 and transversely extending cross beams 13, one of which appears in Fig. 1.

The improved hay rack fastener herein

disclosed is partly formed from a blank of sheet metal 14 having its intermediate portion bent to form a U-shaped bolster engaging member 15. The U-shaped bolster 60 engaging member 15 includes a bearing plate 16 adapted to be mounted upon the top of the bolster and depending sides 17 adapted to engage the sides of the bolster to prevent longitudinal movement of the 65 device with relation to the bolster. Upwardly inclined arms 18 extend from the lower ends of the side members 17 and have their upper portions 19 curved downwardly and arranged in the horizontal plane of the 70 bearing plate 15 for forming additional bearing surfaces for the hay rack bed. As illustrated in Fig. 1, a pair of U-bolts 20 have their bight portions 21 engaged with the under sides of the arms 18 inwardly of 75 the curved portions of the same for securing the fastener to the hay rack bed. The downwardly curved terminals of the arms 18 serve to prevent the bight portions of the U-bolts from accidental disengagement 80 with the arms 18. The shanks 22 of the U-bolts 20 extend on opposite sides of the longitudinal beams 12 and extend through attaching straps 23 mounted on the tops of the beams 12. Nuts 24 have threaded 85 engagement with the shanks 22 of the U-bolts and are adapted to be tightened on the same for rigidly securing the device to the hay rack bed.

When the device is applied to the bolster 90 as outlined the depending sides of the U-shaped bolster engaging member 15 prevent longitudinal movement of the hay rack bed with relation to the wagon. As is obvious from Fig. 1, the hay rack bed may be 95 adjusted to any desired position with relation to the bolster for displacing the load as desired.

In arranging the device between the hay 100 rack bed and the bolster all wearing between the hay rack bed and the bolster as the result of friction is eliminated.

In arranging the plate 15 in close contact with the under side of the bed rack, water is prevented from lodging between 105 the device and the hay rack with the result that the hay rack is prevented from rotting at its point of connection with the bolster.

With reference to the foregoing description taken in connection with the accompanying drawings, it will be noted that the 110 hay rack fastener herein disclosed may be

conveniently applied and serves to absolutely secure the hay rack in an adjusted position with relation to the bed rack whereby all relative movement between the 5 hay rack and the wagon is eliminated.

It is to be understood that the form of the invention herewith shown and described is to be taken as a preferred embodiment of the same and that such minor changes 10 may be made as will remain within the spirit of the invention and the scope of what is claimed.

Having thus described the invention, what is claimed as new is:

15 1. A device of the class described including a sheet metal inverted U-shaped member, upwardly inclined arms extending from the terminals of the sides of said member and having their upper extremities curved 20 outwardly and downwardly, and clamping members seating in the concavities of said curved extremities.

2. The combination with a wagon bolster, and a hay rack superimposed thereon, of an inverted U-shaped member having an intermediate portion extending across the top of the bolster and depending sides engaging the sides of the bolster, the hay rack having a beam resting directly on the intermediate portion of the said member, inclined arms extending upwardly and outwardly from the lower ends of the sides of said member, the terminals of said arms being curved downwardly and outwardly, U-bolts engaging beneath the terminals of the 35 arms in the bases of the curves thereof and passing upwardly at the sides of the hay rack, clamping plates disposed transversely over the rack beam and fitting over the extremities of the U-bolts, and nuts fitted on 40 the ends of the U-bolts and turned home against said plates.

In testimony whereof I affix my signature.

HOWARD A. SMITH. [L.S.]
